US0D1080530S

(12) **United States Design Patent** (10) **Patent No.:** **US D1,080,530 S**
(45) **Date of Patent:** **** Jun. 24, 2025**

(54) **CHARGING CASE FOR EARPHONES**

(71) Applicant: **BEIJING XIAOMI MOBILE SOFTWARE CO., LTD.**, Beijing (CN)

(72) Inventors: **Huacan Cui**, Beijing (CN); **Jiasheng Huang**, Beijing (CN)

(73) Assignee: **BEIJING XIAOMI MOBILE SOFTWARE CO., LTD.**, Beijing (CN)

(**) Term: **15 Years**

(21) Appl. No.: **35/519,142**

(22) Filed: **Nov. 29, 2022**

(80) **Hague Agreement Data**

Int. Filing Date: **Nov. 29, 2022**

Int. Reg. No.: **DM/225365**

Int. Reg. Date: **Nov. 29, 2022**

Int. Reg. Pub. Date: **Dec. 1, 2023**

(30) **Foreign Application Priority Data**

Jun. 2, 2022 (CN) 202230337526.4

(57) **CLAIM**

The ornamental design for a charging case for earphones, as shown and described.

DESCRIPTION

1. Charging case for earphones

1.1 : Front

1.2 : Back

1.3 : Left

1.4 : Right

1.5 : Top

1.6 : Bottom

1.7 : Perspective

1.8 : Perspective

1.9 : Front

1.10 : Back

1.11 : Left

1.12 : Right

1.13 : Top

1.14 : Bottom

1.15 : Perspective

1.16 : Perspective

1.1 is a front view of a charging case for earphones, shown in a closed state; 1.2 is a rear view thereof; 1.3 is a left view thereof; 1.4 is a right view thereof; 1.5 is a top view thereof; 1.6 is a bottom view thereof; 1.7 is a front perspective view thereof, 1.8 is a rear perspective view thereof; 1.9 is a front view of the charging case for earphones, shown in an open state; 1.10 is a rear view thereof; 1.11 is a left view thereof; 1.12 is a right view thereof; 1.13 is a top view thereof; 1.14 is a bottom view thereof; 1.15 is a front perspective view thereof, and 1.16 is a rear perspective view thereof. The broken lines in the reproductions illustrate portions of the article that form no part of the claimed design.
